UNITED STATES PATENT OFFICE.

WILLIAM R. ALLEN, OF CLEVELAND, OHIO, ASSIGNOR TO THE AMERICAN MULTIGRAPH COMPANY, OF CLEVELAND, OHIO, A CORPORATION OF OHIO.

PROCESS OF MAKING PRINTING-SLUGS.

1,122,841.

Specification of Letters Patent.

Patented Dec. 29, 1914.

Application filed June 18, 1914. Serial No. 845,753.

To all whom it may concern:

Be it known that I, WILLIAM R. ALLEN, a citizen of the United States, residing at Cleveland, in the county of Cuyahoga and State of Ohio, have invented a certain new and useful Improvement in Processes of Making Printing-Slugs, of which the following is a full, clear, and exact description, reference being had to the accompanying drawings.

This invention relates to printing slugs adapted to stand a short height-to-paper and of a form which may be readily mounted in grooved or slotted holders, as, for example, the multigraph drum, slotted type plates, etc.

The objects of the invention are to provide such a slug in a form which will be effective in service and which may be easily and cheaply manufactured.

The present application is concerned with the process of making a slug comprising forming a primary slug and thereafter treating it in a peculiar manner to obtain the finished product. The printing slug formed by this process is claimed in my divisional application No. 869,750, filed November 2, 1914.

The invention comprises broadly the casting of a slug in a T-form and the submitting of the shank of the slug to pressure from opposite sides to form protuberances on the sides of the shank some distance below the head, and the cutting-off of the shank below these protuberances. The protuberances constitute, in effect, ribs on opposite sides of the slug which are effective to prevent its dropping out of the groove or slotted holder.

This invention is illustrated in the drawings hereof and is hereinafter more fully described and its essential characteristics are set out in the claims.

In the drawings, Figure 1 is a section through a mold wheel, melting pot and matrix of a suitable casting machine arranged to cast a T-headed slug; Fig. 2 is a section through the mold wheel along the casting slot showing the cast slug in position; Fig. 3 is a perspective view of a portion of the slug cast by the mechanism shown in Figs. 1 and 2; Fig. 4 is a perspective view of the finished slug after it has been treated to produce the corrugations corresponding to ribs on the

sides of the shank; Fig. 5 is a fragmentary plan of a pair of crimping blades and an interposed shank of the slug (shown in section); Figs. 6 and 7 are vertical sections of mechanism employing such crimping blades for corrugating the slug, —Fig. 6 showing the mechanism in position as the primary slug is inserted and Fig. 7 showing it at the end of the operation of crimping and cutting-off the lower portion of the shank; Fig. 8 is a vertical section on a smaller scale of the complete machine embodying the mechanism illustrated in Figs. 5, 6 and 7; Fig. 9 is a plan on a still smaller scale of such complete machine; Fig. 10 is a plan of the crimping blades on the same scale as Fig. 9.

As shown in Figs. 1 and 2, 1 indicates the mold wheel of the usual Mergenthaler or Intertype line casting machine, 2 indicates the melting pot, and 3 the line of matrices. 4 designates a mold carried by the mold wheel and adapted to be positioned by it between the melting pot and matrices. This mold is formed with a cavity 5 for the shank of the slug and a laterally extending cavity 6 for the T-head of the slug. The sides of the shank are preferably as nearly parallel as they may be and allow the slug to be conveniently ejected from the mold. The ends of the shank cavity are tapered as shown in Fig. 2, the taper being somewhat abrupt as it leaves the head portion of the cavity, as shown at 7, and more gradual for the rest of the end, as shown at 8.

The slug cast by mechanism described is shown in Figs. 1, 2 and 3 and comprises the shank A and the overhanging head, A'. This head has printing characters, as desired. The ends of the shank have the abrupt inward taper a for a comparatively short distance adjacent to the head and then the gradual taper a' for the purpose hereinafter described.

After such slugs as shown in Fig. 3 are cast, the shanks are suitably crimped or corrugated some distance below the head and below such corrugated portions the shank is cut off. Fig. 5 shows a pair of corrugating blades 10 and 11 having complementary wavy or serpentine edges 9. The shank A of the slug is placed between such blades in such position that the blades are a suitable distance below the head of the slug. Then,

when the blades approach each other the portion of the shank between them is bent from one side to the other and corrugated, producing the ribs shown at A² in Fig. 4. 5 This corrugating action tends to force some of the metal beyond the end of the shank, and, in order that this will not extend beyond the head of the slug, the inwardly tapered portion a is provided. The corrugations are made adjacent to the lower end 10 of the taper a, which provides ample room for extension of the shank without its projecting beyond the head.

It will be observed that such a slug as 15 shown in Fig. 4 has, in effect, ribs on its opposite sides some distance below the head of the slug, while the head and the immediately adjacent portion of the shank are left in their original cast form. Accordingly, 20 with the slug having its head accurately cast to stand the right height above the holder, this height is preserved, notwithstanding the subsequent treatment of the slug and the finished slug thus has the desired correct height-to-paper, this finished 25 slug taking its printing pressure on the shoulder provided by the under face of the head. It will be seen, therefore, that my process produces a slug much more accurately dimensioned in the critical part than 30 where the groove is machined into the side of the slug, as experience has demonstrated that it is very difficult to accurately machine such a groove. Moreover, my process does not disturb the original skin of the metal, 35 wherefore the slug is stronger than if such skin were removed by machining. In the conditions of casting present in the Mergenthaler or Intertype machines, it is extremely difficult to prevent blow holes within 40 the slug. Such blow holes are not serious,—if the original skin of the slug is preserved,—but become very serious if any of the metal along the sides of the shank is machined away. My process also does away 45 with the necessity of having a mold adapted to be opened to release the slug, as would result if it were attempted to cast a slug with grooves in its sides. Such openable 50 molds reduce the accuracy of the resulting product and increase the complexity and expense of the mechanism. With my process a very simple solid mold is substituted for the usual mold in the line casting machine and the different parts of the machine 55 coact with this mold in the usual manner.

It is convenient to crimp the sides of the shank and cut off the excess of shank below the crimped portion at the same operation. 60 Mechanism for accomplishing this is shown in Figs. 6 and 7, wherein corrugating blades 10 and 11 are secured to knives 12 and 13. Secured to these knives are shown blocks 14 and 15 which have edges 16 and 17 respectively, so placed that they are adapted

to engage and center the head of the primary slug as the knives and pressing blades come to their innermost position. In the space above the crimping blades are a pair of centering blades 18 and 19 which are designed to engage the shank of the slug immediately below the head and above the region to be corrugated. These centering blades have a slight backward and forward movement within the respective blocks 14 and 15 and are pressed toward each other by springs 20 and 21 bearing against pins 23 and 23 which abut the ends of the blades 18 and 19. The knife 12 and the block 14 are secured to a suitable stationary bed 24 while the corresponding knife 13 and block 15 are secured to a movable block 25. When the mechanism described is in the open position, as shown in Fig. 6, there is a sufficient space between the centering blades 18 and 19 and the crimping blades 10 and 11 for the easy insertion of the shank of the slug. At the same time the blades 18 and 19 are positioned so that the head of the slug may rest upon and be supported by them. This is accomplished by the springs 20 and 21 pressing these blades toward each other to the limit provided by heads 26 and 27 on the blades engaging the walls of corresponding recesses in the blocks 14 and 15. When the crimping blades are nearest together, the centering blades 18 and 19 engage the shank of the slug just beneath the head, the shoulders 23^a formed in the blocks 14 and 15 causing them to tightly grip the slug to preserve its exact shape for the proper distance beneath the head, at the same time squaring the upper side of the corrugated ribs A², as shown in Fig. 4.

When the slug is in position, as shown in Fig. 6, the block 25 is moved toward the bed 24. In this movement the spring pressed blades 18 and 19 recede into their respective blocks until their rear ends abut the outer wall of the recesses in the blocks, as shown in Fig. 7. Before these blades reach this abutting position, the crimping blades and the knives will have begun to act on the opposite sides of the shank, and, as the block 25 reaches its final position in its approach toward the bed 24, the knives will have sheared entirely through the shank, the crimping blades will have corrugated a strip of the shank above such knives, the centering blades will have held intact the shank above such corrugated portion, and the face of the blocks will have held the head in position. This final position is shown in Fig. 7. As a result of such operation, the lower portion of the shank trips off and a slug of the form shown in Fig. 4 is produced.

Figs. 8, 9 and 10 show a more complete machine for producing the crimping and shearing of the slug shank just described. In this complete machine the crimping

blades 10 and 11 preferably extend beyond the blocks 14 and 15 and are secured by screws 30 to the respective knives, these screws passing through slots 31 in the crimping blades. This construction enables the knives to be adjusted relatively inward of the crimping blades as the knives wear in operation. The blades at their edge opposite the crimping edge abut the wall of the recess in the blocks 14 and 15, which, with the knives, are secured, as explained, to the bed 24 or the movable slide 25. Suitable set screws 34 and 35 screwing through the bed and block respectively adjust the knives and parts carried thereby.

It is convenient to make the bed 24 as a portion of the main form of the machine and to mount the slide 25 thereon as shown in Fig. 8. Any suitable means may be employed to force the slide toward the coöperating member. For this purpose I may employ mechanism shown in application No. 835,478, of Harry C. Gammeter for moving suitable dies for producing another operation on the shank of line slugs. The said Gammeter application should be referred to for claims on whatever is common to that application and this. As stated, one of the common features is the mechanism for operating the slide, which will now be described.

The slide 25 is shown as having its rear edge inclined (Fig. 9) and provided with a downwardly projecting rib 40. Behind this slide is a wedge 41 which has a diagonal rib 35 extending in front of the rib 40. Accordingly, the slide is carried to the wedge for a movement toward or from the stationary dies while the wedge may move longitudinally of the slide and thus force it laterally. To move the wedge longitudinally it is provided with a rack 45 with which meshes a segment 46 which is pivoted at 47 and formed beyond the pivot into an operating lever 48. Set screws 50 and 51 limit the movement of the wedge in each direction. To hold the slug firmly down between the dies during the operation a rocking frame 55 is provided which has a roller 56 adapted to rest on the face of the slug and an operating handle 57. A suitable set screw 58 limits the downward movement of the roller so that the slug may be held accurately pressed down upon the centering dies.

In operating the machine shown in Figs. 8, 9 and 10 the cast T slug is inserted by hand between the pressing devices and the lever 57 is shoved over to press the slug down in position and the lever 48 is drawn forwardly to shift the wedge to force the movable die and knife against the shank of the slug, thus crimping the shank and cutting off the portion below the crimped ribs. By using a hard rubber roller 56 I can hold the slug firmly in position during this operation without injuring the face of the char-

acters. The roller gradually works around to present different portions so that it is not unduly worn.

Having thus described my invention, what I claim is:

1. The process of making slugs consisting of forming the slug in a T-shape and submitting the shank to pressure adapted to produce protuberances on the opposite sides thereof. 70

2. A process of making slugs adapted to stand a short height-to-paper consisting of originally forming the slug in a T-shape and thereafter corrugating the same to produce protuberances on the opposite sides of the shank and removing the shank below the corrugations. 75

3. The process of forming printing slugs consisting of casting the slug in a T-shape and by pressure oppositely bending the shank thereof some distance below the T-head. 85

4. The process of forming printing slugs consisting of casting the slug in a T-shape, corrugating the shank thereof some distance below the T-head and removing the shank below the corrugations. 90

5. The process of forming printing slugs consisting of casting the slug in a T-shape and thereafter submitting the shank to pressure on opposite sides to bend laterally a strip of the shank parallel with and some distance below the head. 95

6. The process of forming printing slugs consisting of casting the slug in a T-shape and thereafter submitting the shank to pressure on opposite sides to bend laterally a strip of the shank parallel with and some distance below the head and at the same time removing the shank below the laterally bent portions. 105

7. The process of making printing slugs consisting of forming a slug with a shank and corrugating the shank to produce lateral projections. 110

8. The process of making printing slugs consisting of forming a slug with a shank and corrugating the shank to produce lateral projections and removing the shank below the projections. 115

9. The process of making a slug having the effect of one cast with grooves in its sides consisting of casting a T-headed primary slug and thereafter by pressure corrugating the shank thereof. 120

10. The process of making printing slugs consisting of casting the slug in a T-shape with a head and a shank and thereafter pressing part of the shank some distance below the head beyond the plane of one side of the shank and pressing another part of the shank beyond the plane of the opposite side thereof. 125

11. The process of making printing slugs consisting of casting the slug with an over- 130

hanging head and a shank, and thereafter pressing inwardly against the side of the shank at separated spots in a row some distance below the head to cause the shank to be indented and protuberances formed opposite the indentations.

12. The process of making printing slugs consisting of casting the slug in a T-shape with a smooth-sided shank and thereafter 10 pressing inwardly against each side of the shank at separated spots some distance below the head, such spots on one side of the shank being out of registration with those on the other, whereby material of the 15 shank is forced outwardly in opposite directions to produce projections alternately on opposite sides of the shank.

13. The process of making printing slugs consisting of casting the slug with an over- 20 hanging head and a shank, and after the slug is removed from its mold submitting the shank to pressure from each side at separated spots in a row some distance below the head and parallel therewith, the spots on 25 opposite sides of the shank being out of

registration with each other, whereby the shank is indented alternately from opposite sides and resulting protuberances formed.

14. The process of making printing slugs consisting of casting the slug with a T-head 30 and a smooth-sided shank and after the slug is removed from its mold submitting the shank to pressure from each side at separated locations in a row some distance below the head and parallel therewith, and shearing off the portion of the shank below the parts pressed, the parts pressed on opposite sides of the shank being respectively out of registration with each other, and said pressure being sufficient to indent the sides of 40 the shank and press protuberances outwardly from the opposite sides thereof.

In testimony whereof, I hereunto affix my signature in the presence of two witnesses.

WILLIAM R. ALLEN.
